PHONOGRAPH SYSTEM

Merrill L. Bradfield, Terre Haute, Ind., assignor
to Thomas A. Edison, Incorporated, West
Orange, N. J., a corporation of New Jersey

Application March 10, 1938, Serial No. 195,026

10 Claims. (Cl. 179—6)

This invention relates to phonograph systems and more particularly to means for controlling and adapting phonograph-recording systems to perform a plurality of functions. It is primarily concerned with phonograph-recording systems which are arranged so that they may be operated to transmit sounds and conversations as for inter-office communicating purposes.

It is another object to provide in a system of sound recording and sound transmitting, means for controlling and adapting the system for any one of its several specific functions by a single manipulation of a switch device.

It is another object to provide in a system of sound recording and sound transmitting, a plurality of control stations respectively having sound-transmitting and sound-receiving devices and control means operable to provide one-way sound transmitting facilities therefrom, of which at least one of the control means is operable to adapt the system for sound recording.

Other and allied objects will more fully appear from the following description and the appended claims.

In the description of my invention, reference is had to the accompanying drawing which is a schematic diagram of a phonograph-recording system in which my invention is incorporated.

The portion of the accompanying drawing which comprises the phonograph A may first be described. This phonograph may be of any suitable variety for receiving and recording sound-representing electric oscillations. In a form such as is common in the recordation of dictation and other conversations the phonograph A may comprise a mandrel 1 adapted for removably carrying a cylindrical record 2; a carriage 3 bearing a sound-translating device 4 adapted for recording on the record 2, the carriage 2 being adapted to be driven longitudinally of the record 2 as along a guide rod 5 by means of a feed screw 6; a motor 7 suitably arranged to provide rotational movement of the mandrel and longitudinal movement (in a right-hand direction) of the translating device; a train of gears 8 coupling the feed screw 6 with the mandrel 1; and a clutch 9 interposed between the mandrel 1 and the driving means therefor.

The translating device 4 is adapted, when in an operative condition, to receive electric oscillations, as by way of the terminals 10, and to impress or cut on the surface of the record 2 a progressive groove modulated in accordance with those oscillations. The means for rendering the translating device operative and inoperative may comprise a control lever 11 (well known in the art) having respective operative and inoperative positions. When the translating device 4 is adjusted to an inoperative position it is removed from engagement with the record 2, thereby permitting the removal of the record 2 from the

10 elements there may be conveniently provided a simplified form of a combined sound-recording and sound-transmitting system. Since sound-recording systems are commonly employed for the recordation of dictation and business conversations by those who often have need for inter-office communicating equipment, it is highly desirable for reasons of economy and facility of operation, to provide such means as will permit a phonograph-recording system to fulfill also the function of a sound-transmitting system. Such a combined system of sound recording and sound transmitting may be arranged for the use of any plurality of operators of which any number of the operators may be provided with facilities for sound recording and/or one or two way sound transmission. This system may moreover be controlled and/or operated by conveniently arranged control means facilitating the use of the system.

40 It is an object of my invention to provide, in a phonograph-recording system, means whereby the recording system may fulfill a plurality of functions.

It is another object to provide an economical arrangement of a combined phonograph-recording and sound-transmitting system which is conveniently arranged for easy control and operation.

50 It is another object to provide, in a phonograph-recording system, a plurality of electro-acoustical devices and a plurality of control devices whereby the system may be operated for sound recording purposes from one or more locations and may also be adapted for sound-trans-

mandrel 1. The control lever 11 is also commonly arranged to control suitable means for coupling and uncoupling the carriage 3 with the feed screw 6 as it is moved to its respective operative and inoperative positions.

An electrical phonograph-recording system comprises, in addition to the phonograph A, suitable electro-acoustical means for receiving sound waves and translating these waves into corresponding electric oscillations. Such electro-acoustical means may be of any suitable variety, such as a microphone or telephone. These means may be located, if desired, in the room in which the phonograph A is located. It will be understood, however, that the location of the phonograph with respect to that of the electro-acoustical means is relatively unimportant as long as they are separated sufficiently to avoid feedback. The phonograph A may, for example, be very desirably located in a room 12, or other suitable location, and the electro-acoustical device or microphone 13 in another room such as 14.

The output of the microphonet 13 is usually of relatively low level and therefore suitable means for amplifying the microphone output is provided, such as the electrical amplifier 15 which feeds into the translating device 4, as by way of the circuit 16. The output of the microphone 13 is also very desirably controlled by a suitable attenuating means or volume control 17 which is serially connected in a circuit 18 leading from the microphone 13. During periods of temporary non-use of the machine it is desirable to have the microphone 13 disconnected from the amplifier 15, as such connection may tend to cause extraneous and objectionable sounds to be radiated from the translating device 4 during such periods. These radiated sounds may moreover tend to be fed back into the microphone 13 and cause objectionable howling sound effects. In order that the microphone 13 may be disconnected from the input of the amplifier 15, the circuit 18 is connected with the pole members 19 and 20 of a multiple switch 21 having upward and downward closed positions and a central open, or neutral position. When the switch 21 is in its downward position these respective pole members are closed with the contact members 22 and 23 to make connection with the input of the amplifier 15 by way of the circuit 24.

During periods of non-use of the phonograph-recording system, it is desirable that the phonograph be inoperative. The phonograph may be rendered inoperative and operative simultaneously with the disconnection and reconnection of the microphone 13 with the amplifier 15. To effect such control of the phonograph there is provided suitable switch means comprising the pole member 25 and the contact member 26 of the multiple switch 21. These switch means are arranged to close a circuit 27 to connect the motor 1 with a suitable source of power, as the switch 21 is operated from its neutral position to its downward closed position. By this means record rotation is started and stopped to put the phonograph into and out of operation as the microphone 13 is respectively connected with and disconnected from the amplifier 15. The manner by which the phonograph A is to be put into and out of operation is however an arbitrary one since such control of the phonograph may, for example, be also effected by any suitable means for operating the clutch 9 or the control lever 11.

It may be desirable to provide a plurality of

means whereby the phonograph A is operable by any one of a group of operators. Such additional means may, for example, be placed in a location or room 28; in the drawing they have been designated with numbers similar to those for the corresponding components as provided in room 14 but having prime marks—such as a microphone 13', a volume control 17', and a multiple switch 21'. As in the case of the switch 21, the switch 21' is provided with the pole members 19' and 20' and the contact members 22' and 23' for closing and opening a circuit adapted to connect the microphone 13' with the input of the amplifier 15, and with the pole member 25' and contact member 26' for closing and opening the power supply circuit 27 for the motor 1.

In order that the phonograph A may not tend to be operated by more than one operator at any one time, there is provided a signaling system, which may be of any suitable variety, whereby each operator will receive a signal whenever any one operator places the phonograph A in an operative condition. Such a signaling system may, for example, comprise a plurality of signal lamps, one for each phonograph control switch, such as the lamps 29 and 29' for the respective switches 21 and 21', each of which are connected across the motor 1, as by the respective circuits 30 and 30'. Thus each of these lamps are lighted whenever the phonograph A is put in an operative condition.

A phonograph recording system, as heretofore described, comprises the basic elements of a sound transmitting system. By proper arrangement and control of these basic elements, as according to my invention, they may be utilized in a combined phonograph-recording system and sound-transmitting system such as is commonly used for inter-office communicating purposes. These normally separately attained functions of sound recording and sound transmitting may therefore be effected with one integrated installation. This integrated installation may then be of simple and economical arrangement, and easily adapted to effect any one of its specific functions.

In order that the operator of microphone 13, located in room 14, may communicate with an operator in some other location, which may be that of room 28, there is provided a sound reproducer 31 in the room 28. This sound reproducer 31 is adapted to be connected across the output of the amplifier 15, as by way of the circuit 32, at the will of the operator in room 14 by the manipulation of the multiple switch 21 to its upward position, this connection being effected by the provision of a pole member 33 and contact member 34 which are interposed in the circuit 32 and which are closed with each other as the switch 21 is operated to its upward position. In order that the operator in room 28 may also communicate with the operator in room 14, there is also provided a sound reproducer 31', such as 31, which is located in room 14. The sound reproducer 31' is also adapted to be connected across the output of the amplifier 15, as by way of the circuit 32', at the will of the operator in room 28 by the manipulation of the multiple switch 21' to its upward position. As in the case of the switch 21, this connection is effected by the pole member 33' and contact member 34' which are interposed in the circuit 32' and which are closed with each other as the switch 21 is operated to its upward position.

Whenever the sound transmitting system is

conditioned for two way sound transmission there are placed in the same vicinity, or room, a microphone and sound reproducer respectively connected across the input and output of the amplifier 15. There will then tend to be acoustic feedback between the microphone and sound reproducer because of their juxtaposition. Moreover, the amplifying requirements are usually considerably greater for a sound-recording system than for a sound-transmitting system, and therefore, in a combined sound-recording and sound-transmitting system this feedback tendency is greatly augmented. It is however a feature of my invention to provide simple means by which the effective gain of the system is adjusted to a proper value whenever it is to be used for sound-transmitting purposes, thereby mitigating the tendency for acoustical feedback. The means for effecting this adjustment comprises an attenuator 35 which is automatically interposed into the circuit connecting the microphone 13 with the input of the amplifier 15 as the switch 21 is thrown into its upward position. In order that the attenuator 35 may be so interposed, it is serially provided in a circuit 36 which is connected from the contact members 22 and 23 to a set of contact members 31 and 38 respectively arranged for closing with the pole members 19 and 20 as the switch 21 is thrown to its upward position. Thus the gain of the system is properly adjusted and the sound reproducer 31 is simultaneously connected across the amplifier output so that the system is properly conditioned for one way sound transmission as the switch 21 is thrown to its upward position. It will be understood that according to my invention the means whereby the gain of the system is properly adjusted for sound recording and sound transmitting is an arbitrary one, as such adjustment of the gain may be effected in many suitable ways.

The switch 21' may be in all respects similar to the switch 21, it being provided with the contact members 31' and 38' corresponding to the contact members 31 and 38 of the switch 21. Between the set of contact members 31' and 38' and the set 22' and 23' there is interposed a circuit 36' which is serially provided with an attenuator 35' such as the attenuator 35. As the switch 21' is thrown to its upward position the contact members 31' and 38' are closed with the respective pole members 19' and 20' to connect the microphone 13' with the input of the amplifier 15, and the pole member 33' is closed with the contact member 34' to connect the sound reproducer 31' across the output of the amplifier 15, thereby conditioning the system for one way sound transmission as from the microphone 13'.

As the switches 21 and 21' are in their respective neutral or upward positions the power circuit 27 is open and the phonograph A is rendered inoperative. The phonograph A is however put in operative condition whenever either of the switches 21 and 21' is operated to its downward position to condition the system for sound recording.

During the non-use of the system each operator will normally have his respective control switch in its neutral position. If either operator should desire to record, he will place his control switch in its recording position, thereby operating the signalling system to inform the other operator that the phonograph A is in an operative condition. If however either operator should desire to communicate with the other he will operate his

control switch to its upward position, and the other operator, in order to provide two-way communication, will also operate his control switch to its upward position.

Although I have illustrated my invention with a specific embodiment it will be understood that many changes and modifications may be made therein without departing from the scope of my invention. There may, for example, be provided any plurality of electro-acoustical devices and of control means for connecting these devices into the system and for controlling the phonograph, as desired. These electro-acoustical devices may be connected into the system singly or in any suitable combination so that any operator may communicate with any other or any group of operators. Such and other modifications will not necessarily depart from the scope of my invention which I undertake to express according to the following claims.

I claim:

1. The combination in a system comprising a phonograph having means for rotating a record and a translating device cooperating with said record of an electrical amplifier connected to said translating device; a microphone for the input of said amplifier; a sound reproducer for the output of said amplifier; and a unitary switch device having a position for connecting said microphone and said sound reproducer with said amplifier, and another position for connecting said microphone with said amplifier and for rendering said record-rotating means operative.

2. In a system of the character described, the combination of a phonograph having means for moving a record and a translating device adapted to cooperate with said record; an electrical amplifying arrangement adapted for connection in the system so as to function either with a normal gain or a modified gain; an electro-acoustical source of oscillation; a sound reproducer associated with the output of said amplifying arrangement; and means operable to connect said source of oscillation with said reproducer through said amplifying arrangement with the latter connected in the system so as to function with such modified gain, and also operable to render said phonograph operative and simultaneously to connect said electro-acoustical source of oscillation with said translating device by way of said amplifying arrangement with the latter connected in the system so as to function with a normal gain.

3. In a system of the character described, the combination of a phonograph having means for moving a record and a translating device cooperating with said record; an electro-acoustical source of oscillations; a sound reproducer; and adjustable means including a controllable amplifying arrangement, selectively operable to render said record-moving means operative and simultaneously to amplify said oscillations with normal gain and feed the same into said translating device, and to amplify said oscillations with a modified gain and feed the same into said reproducer.

4. A system for phonograph recording and interoffice communicating purposes comprising means for rotating a record; a translating device cooperating with said record; an electrical amplifier connected to said translating device; attenuating means connected to said amplifier; a microphone; a sound reproducer for the output of said amplifier; and switch means having a position for simultaneously rendering said phonograph operative and connecting said microphone

- with said amplifier to put said system in operation for recording, and having another position for simultaneously connecting said microphone with said attenuating means and said sound reproducer with said amplifier to put said system in operation for inter-office communication.
5. A system for recording and transmitting sounds and conversations comprising phonograph recording means; record-rotating means for said recording means; an electrical amplifier connected to said recording means; attenuating means connected to said amplifying means; a plurality of control stations each comprising a microphone; a sound reproducer and a switch means, each of said switch means having a position for simultaneously rendering said record-rotating means operative and connecting the microphone of the control station with the input of said amplifier, and having another position for simultaneously connecting the microphone of its control station with the input of said attenuating means and a sound reproducer of one of the other control stations with the output of said amplifier.
10. 6. In a system of the character described, the combination of a phonograph having record-moving means and a record-cooperating sound translating device; means for amplifying oscillations fed to said translating device, having an input and an output; and a plurality of control stations each comprising a microphone, a sound reproducer and a switch means, each of said switch means being selectively operable to connect the microphone of its control station with the input of said amplifying means and to coordinate render said record-moving means operative, or to render said record-moving means inoperative and to coordinate connect the microphone of its control station and a sound reproducer of one of the other of said control stations with the input and output of said amplifying means respectively.
15. 7. The combination as claimed in claim 6, wherein each of said switch means is further selectively operable to render said record-moving means inoperative and to coordinate disconnect both the microphone of its control station and the sound reproducer of the said other control station from said amplifying means.
20. 8. A system for recording and transmitting sounds and conversations comprising phonograph recording means; and a plurality of control stations each comprising a microphone, a sound reproducer and a unitary switch device, each of said unitary switch devices including
25. means operable at will to connect the microphone of its control station with a sound reproducer of one of the other control stations to form a one-way sound communicating channel between said control stations, and at least one of said switch devices including means for rendering said phonograph recording means operative, at will, to permit the recordation of sound from the microphone associated with said one switch device.
30. 9. In a system of the character described, the combination of a phonograph having record-moving means and a record-cooperating sound translating device; an amplifying arrangement connectable so as to function either with a normal gain or a modified gain; and a plurality of control stations each comprising a microphone, a sound reproducer and a switch means, each of said switch means having a position for connecting the microphone of its control station with the sound reproducer of at least one of the other control stations by way of said amplifying arrangement with the latter connected so as to function with a modified gain, and having another position for rendering said record-moving means operative and concurrently connecting the microphone of its control station with said translating device by way of said amplifying arrangement with the latter connected so as to function with a normal gain.
35. 10. In a system of the character described, the combination of a phonograph having record-moving means and a record-cooperating sound translating device; means for amplifying oscillations fed to said translating device, having an input and an output; and a plurality of control stations each comprising a microphone, a sound reproducer and a switch means, one of said switch means having a position for connecting the microphone of its control station with the input of said amplifying means and coordinate rendering said record-moving means operative and another position for rendering said record-moving means inoperative and coordinate connecting the microphone of its control station and the sound reproducer of at least one of the other of said control stations with the input and output of said amplifying means respectively, and the other of said switch means being respectively operable to concurrently connect, at will, the microphone of their respective control stations and the sound reproducer of at least one of the other control stations with the input and output of said amplifying means respectively.
